Primary Examiner — Susan Moon Lee

(57) **CLAIM**

The ornamental design for an ergonomic training bowl as shown and described.

DESCRIPTION

FIG. 1 is a front perspective view of an ergonomic training bowl in accordance with the present design.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.
